(57) **CLAIM**

I claim the ornamental design for the cover for rail attachment, as shown and described.

DESCRIPTION

The present invention is the ornamental design for the cover for rail attachment. The nature and environmental use of the claimed design is as follows: The cover may be a plastic, wood, or metal cover, though plastic covers are presently preferred. A plastic cover may be formed from an extruded material, such as vinyl. The cover has an opening that receives an end of a rail. The cover hides or covers the attachment of the rail to a support post.

FIG. 1 is a perspective view of a cover for a rail attachment according to the present invention;

FIG. 2 is a top view of the cover for a rail attachment;

FIG. 3 is a view of a first side of the cover for a rail attachment;

FIG. 4 is an upside-down view of a second side of the cover for a rail attachment;

FIG. 5 is a view of a third side of the cover for a rail attachment; and,

FIG. 6 is a view of a fourth side of the cover for a rail attachment.

Ordinarily, the bottom of the cover will not be visible when the cover is in use as a cover for a rail attachment.
